UNITED STATES PATENT OFFICE.

CLARENCE D. PRUDEN, OF ST. PAUL, MINNESOTA.

SHEET-METAL WINDOW.

SPECIFICATION forming part of Letters Patent No. 711,526, dated October 21, 1902.

Application filed February 17, 1902. Serial No. 94,419. (No model.)

To all whom it may concern:

Be it known that I, CLARENCE D. PRUDEN, a citizen of the United States, residing at St. Paul, in the county of Ramsey and State of 5 Minnesota, have invented certain new and useful Improvements in Sheet-Metal Windows, of which the following is a specification.

My invention relates to improvements in fireproof windows, its object being particularly to provide improvements in the construction of swinging sash and the adjacent framework of fireproof windows, as hereinabove more particularly described and claimed.

In the accompanying drawings, forming 15 part of this specification, Figure 1 is an inside view of a portion of one side of the frame and pivotal support. Fig. 2 is an isometric view of the same with the sash closed. Fig. 3 is a section on line *xx* of Fig. 2, and Fig. 4 is a 20 section on line *yy* of Fig. 2.

In the drawings, A represents one side of the window-frame formed in cross-section of a single piece of metal. Each side member of the window-frame is formed with an opening 2 to receive the supporting-pivot 3, secured to the sash B by means of bolts 4, passing through the sash. Each side member above the pivotal opening 2 is formed with an inturned portion 5, constituting a flange 30 or tongue 9, extending from the top of the window-frame to the sash-pivot, and the lower portion of each side member of the frame is formed with an inwardly-turned lip 6, constituting a groove or cap extending 35 from the pivotal support of the sash to the bottom of the window. Each side member of the sash, as shown in the drawings, is composed of a single piece of metal bent upon itself to form a straight flange or tongue 7, extending 40 from the pivot to the bottom of the sash, and with a cap 8, extending from the pivot to the top of the sash. The pivot 3 is secured to the sash intermediate of the tongue 7 and cap 8. The sash is also bent to form 45 a suitable rest for the glass. (Not shown.)

It will be understood that both side members of the frame and sash are similar in construction.

The top and bottom rails of the sash and 50 frame may be of any desired construction.

With the sash pivotally supported in the frame, as shown in the drawings, the sash is adapted to be swung upon its pivot into open position, as shown in Fig. 1. When the sash is turned to closed position, the tongue 7, carried by the sash below its pivots, will pass into the cap 6, carried by the side member of the frame, and the tongue 9, carried by the side member above the pivot, will fit into the cap 8, carried by the sash, thus constituting 55 an overlapping joint between the sash and frame.

It will be noted that the construction of sash and frame above the pivot is the reverse of that below the pivot.

Among the important features of my invention is the single-piece construction in cross-section of sash and frame. There are thus no parts to become unsoldered and separated in case of fire.

I claim—

1. In a fireproof window, the combination of the side pieces of a window-frame each formed of a single piece of sheet metal in cross-section, and a sash pivoted therein, each 75 side of the sash being formed of a single piece of sheet metal in cross-section, the side pieces of said sash and frame being each bent upon itself to form coöoperating flanges and caps.

2. In a fireproof window, the combination 80 of the side members of the frame, each formed of a single piece of sheet metal in cross-section, a sash pivotally supported therein, each side of the sash being formed of a single piece of metal in cross-section, the sash upon one 85 side of said pivot being bent upon itself to form a cap, the adjacent frame being bent upon itself to form a flange fitting in said cap, the frame upon the opposite side of said pivot being bent upon itself to form a cap and the 90 adjacent sash being bent upon itself to form a flange fitting in said cap.

In testimony whereof I affix my signature in presence of two witnesses:

CLARENCE D. PRUDEN.

Witnesses:

H. S. JOHNSON,
EMILY EASTMAN.
